UNITED STATES PATENT OFFICE.

JOHN GOOD, OF BROOKLYN, NEW YORK.

VALVE MECHANISM

1,156,991.

Specification of Letters Patent. Patented Oct. 19, 1915.

Application filed March 3, 1914. Serial No. 822,247.

To all whom it may concern:

Be it known that I, JOHN GOOD, a citizen of the United States, residing at Brooklyn, in the county of Kings and State of New York, have invented the following-described new and useful Improvements in Valve Mechanisms.

The invention relates to valve gear for internal combustion engines, pumps and like uses, and its object is to obtain the benefits of disk or other rotary valves without the objections arising from the ordinarily high frictional pressure of the disks upon their seats.

15 In accordance with the invention, separate admission and exhaust valves are employed for the inlet and outlet ports of the engine or pump cylinder, and these valves are connected together so that pressure may 20 be transmitted from one to the other and both valves are arranged to be subjected to the pressure within the cylinder. The seats for the valves may be arranged upon the same sides of the valves so that the two 25 valves press in the same direction toward their seats. The pressure within the cylinder is then arranged to act in opposite directions and in unequal degree upon the two valves, as a result of which both will be held 30 against their seats under a pressure which is the resultant of or difference between the two opposing pressures. The pressure within 35 the cylinder can be made to act unequally and in opposite directions upon the valves by arranging the valves on opposite sides of the cylinder or otherwise, whereby unequal areas of them will be exposed oppositely to the pressure fluid.

40 In the accompanying drawing I have illustrated an embodiment of the invention as applied to gas engines, but it will be understood that the invention may be utilized in various other relations.

45 In the drawing the figure is a sectional elevation of a gas or gasoline engine showing the improved form of valve-gear applied thereto.

Referring to the drawing, 2 indicates the cylinder of the engine, mounted upon a 50 crank casing 3 in which the crank shaft 4 is journaled as usual. The cylinder head 5 is water jacketed and forms part of the combustion space 7 at the upper end of the cylinder. This space includes an inlet port 8 and an outlet port 9. To opposite 55 sides of the head 5 are secured the cover

plates 10 and 11, each of which has a passageway formed therethrough aligned with the ports 8 and 9 respectively and constituting an inlet 12 for the combustible vapor and an outlet 13 for the exhaust of the products of combustion. It will be apparent that the precise formation of the parts just described is of no particular consequence and may be varied as occasion demands.

The ports 8 and 9 differ in size, the inlet port 8 being of somewhat greater cross-sectional area than the other. These two ports are controlled by rotary valve-members which are united to each other so that strain may be transmitted directly from one to the other. In the present instance, these valves are shown as disk valves, the disk 14 controlling the inlet port 8 and the disk 15 controlling the outlet port 9, but they might have other forms as will later appear. These two disks are rigidly connected by being mounted upon a valve-shaft 16 which extends across the upper end of the cylinder, through a tubular part 17 of the water jacket with which it need not contact. Each of the two disks 14 and 15 has a port opening therethrough as shown at 18 (in the inlet valve) which opening is adapted to register on the rotation of the shaft with the port 8 or 9, as the case may be, so as to provide a free passage leading to or from the interior of the cylinder. As indicated in the drawing, the seat for the disk valve 14 is upon the adjacent wall of the cover-plate 10 and the seat for the disk-valve 15 is upon the adjacent wall of the head 5, so that some pressure upon the combined valve-members, to the left (in the figure), is necessary to press and maintain them against their seats. This is provided by the extent of the area of the valve 14 exposed to the cylinder pressure, which is larger than the corresponding area of the other valve, and since both are united by the shaft 16 it will be evident, as above pointed out, that both will be pressed against their seats with a pressure less than would otherwise be the case, but nevertheless sufficient to maintain the valves against leakage. The valves are rotated in phase with the crank shaft by a sprocket chain 19 running on sprockets 20 and 21 secured to the shaft 16 and the engine shaft 4, respectively; and it will be evident that such driving connection has but a minimum of work to perform since the friction of the valves on their seats is reduced in the manner above explained.

2
Any suitable means may be provided for mounting the valves 14 and 15 rigidly upon their supporting valve shaft and at the required distance apart. In the drawing, two collars 22 are provided on shaft 16 each bearing against the face of one of the valves 14 and 15 and clamping it against a shoulder on the shaft. These collars 22 are secured by nuts 23 threaded on the shaft 16 and received in cavities provided therefor in the members 10 and 11. By turning these nuts 23 upon the threaded portions of shaft 16, the disks 14 and 15 may be located and held rigidly at the required separation, and if such separation does not happen to be such as to form the best contact with a valve seat, wear of one valve or the other will soon correct the difference.

In the drawing, a slight clearance is provided over the faces of the valves 14 and 15 opposite those which engage the valve seats. In one case, this clearance is on the inner side of the valve and in the other case it is on the outer side. This clearance may be so slight that the valve 14 will not be subjected to the cylinder pressure over the port, because of the effect of its own rotation on the film of fluid seeking to enter the crevice, but if the clearance forming the crevice is of such size that the cylinder pressure may enter it and act on the valve, I prefer to make the valve 14 of such diameter with respect to the valve 15 as to provide nevertheless the desired differential pressure, sufficient to maintain the valves securely seated but less than that which would be effective on either valve if dependent and unconnected.

To maintain the valves normally in engagement with their seats a spring 24 is coiled about the end of shaft 16 bearing at one end upon the bearing 25, and at its opposite end on a washer 26, the latter being adjustably mounted on the reduced threaded end 27 of the shaft 16 by means of nuts 28. These parts are all inclosed within a cover 29 threaded to the cover-plate as indicated. The spring tends to maintain the condition of partial balance between the valves, or restore it if it should be interrupted from any cause, and it will be obvious that it may be arranged in various ways for this purpose, or that other means could be used for the same purpose, and it will also be evident that by balancing the pressure of one valve against the other, by connecting them by a shaft such as 16 as above described, the spring may exert a larger part or indeed

the whole of the seating pressure, depending upon the circumstances of the design. The pressure of the valves against their respective seats will in any event be less than that which would result from the unbalanced action of the pressure in the chamber 7.

Having described my invention, what I desire to secure by Letters Patent is:

1. In apparatus of the kind described, the combination with a pressure chamber, of two rotary valve members united to each other and subject to the chamber pressure in opposite directions, one of said valve members presenting a larger pressure area than the other, whereby said united valve members are subject to differential pressure, and valve seats to which the valves are held by such differential pressure.

2. In apparatus of the kind described, the combination with a pressure chamber of two rotary valves rotated by a shaft to which each is secured and subject to the chamber pressure in opposite directions, one of said valves presenting a larger pressure area than the other whereby both are subject to a differential pressure, and valve seats to which the valves are held by such differential pressure.

3. In apparatus of the kind described, the combination with a pressure chamber, of two rotary valves united to each other and subject to fluid pressure in opposite directions, one of such valves presenting a larger effective pressure area than the other, a valve seat for such valves and means independent of the fluid pressure for urging the valves upon their seats.

4. In apparatus of the kind described, the combination with a pressure chamber, of two rotary valves subject to the same fluid pressure in directions tending to balance the pressure acting on one of said valves against that acting on the other, the valves being connected together so that pressure may be transmitted from one to the other; and means for exerting independent pressure to urge said valves in the same direction toward their respective seats.

In testimony whereof, I have signed this specification in the presence of two witnesses.

JOHN GOOD.
